UNITED STATES PATENT OFFICE

FRANK S. CARLILE, OF ABINGTON, PENNSYLVANIA

DESIGN FOR A BATTERY TESTING STAND

Application filed March 18, 1933. Serial No. 47,512. Term of patent 7 years.

To all whom it may concern:

Be it known that I, FRANK S. CARLILE, a citizen of the United States, and a resident of Abington, county of Montgomery, State of Pennsylvania, have invented a new, original, and ornamental Design for a Battery Testing Stand, of which the following is a specification, reference being had to the ac-

companying drawing, forming a part thereof. The figure represents a perspective of a battery testing stand showing my new design.

I claim:—

The ornamental design for a battery testing stand substantially as shown.

FRANK S. CARLILE.
